US0D1076367S

(12) **United States Design Patent** (10) **Patent No.:** **US D1,076,367 S**
(45) **Date of Patent:** **** May 27, 2025**

(54) **SHOE OUTSOLE**

(71) Applicant: **YOUTH HOME(FUJIAN) SPORTS GOODS CO., LTD.**, Putian (CN)

(72) Inventor: **Jing Guo**, Putian (CN)

(73) Assignee: **YOUTH HOME(FUJIAN) SPORTS GOODS CO., LTD.**, Putian (CN)

(**) Term: **15 Years**

(21) Appl. No.: **29/901,463**

(22) Filed: **Sep. 1, 2023**

(30) **Foreign Application Priority Data**

Apr. 17, 2023 (CN) 202330209564.6

(51) **LOC (15) Cl.** **02-04**

(52) **U.S. Cl.**

(57) **CLAIM**

The ornamental design for a shoe outsole, as shown and described.

DESCRIPTION

FIG. 1 is a first perspective view of a shoe outsole showing my new design;

FIG. 2 is a second perspective view thereof;

FIG. 3 is a left side view thereof;

FIG. 4 is a right side view thereof;

FIG. 5 is a front view thereof;

FIG. 6 is a back view thereof;

FIG. 7 is a top view thereof; and,

FIG. 8 is a bottom view thereof.

The broken lines and lightened areas surrounded by broken lines shown in the drawings depict portions of the shoe outsole that form no part of the claimed design.

1 Claim, 8 Drawing Sheets
